HAIR CUTTER

Francesco D. Infantino, Camden, N. J.

Application November 5, 1952, Serial No. 318,926

4 Claims. (Cl. 30—30)

1

My invention relates to a new and useful hair cutter of the type used by a person to cut or trim his own or to enable one not especially skilled in the art of hair cutting to trim or cut another person's hair.

An object of the invention is to produce an exceedingly simple, effective and durable device of the character mentioned in which a safety razor blade is removably mounted in an adjustable slide travelling in tracks partially contained within a control box or body constantly open at the bottom and also provided with an open upper end normally closed by a lid supporting the adjustable slide or razor blade container and the means for adjusting said slide, the cutting edge of the razor blade being enclosed within a wire guard having the individual elements secured to the control box, said guard being of triangular configuration to provide opposed slanting sides as guides to rest against a person's head during the hair cutting operations.

Another object of the invention is to produce a hair cutter in which both sides of the structure are identical and without lateral protuberances, other than the elements of the guard, whereby the device can be used on either the right or left hand sides of the head without the necessity of making any adjustments after the desired setting of the blade is once obtained.

Another object of this invention is to provide a razor blade container of unique construction including a sliding cover to allow easy access for insertion or removal of a razor blade.

A further object of the invention is to provide an index on the adjustable razor blade container whereby the adjustment of the cutting edge of the blade may be readily and easily determined without resorting to guess work.

A still further object of the present invention is to so construct the appliance that the razor blade container can be inserted and removed through the back of the device, which is normally the top, for the placement of a blade in or the removal thereof from said blade container.

With the above and other objects in view this invention consists of the details of construction and combination of elements hereinafter set forth and then designated by the claims.

In order that those skilled in the art to which this invention appertains may understand how to make and use the same I will describe its construction in detail referring by numerals to the accompanying drawing forming a part hereof, in which:

Fig. 1 is a perspective view of a hair cutter constructed in accordance with my invention.

Fig. 2 is an enlarged section on the line 2—2 of Fig. 1.

Fig. 3 is a perspective view of the razor blade container removed from the hair cutter control

2

box or body and with the cover partially withdrawn.

Fig. 4 is a further enlarged fragmentary section of the control box, cover and latch.

In carrying out the invention as herein embodied 5 represents the hollow control box or body open at the top and bottom and while the bottom is constantly open the top is normally closed by a flat lid 6 resting on the upper edges of the side and end walls of said body. The lid functions as the back of the device and is detachably held in place by suitable means such as latches 7 pivoted on the exterior of said lid and engageable with the hook-like keepers 8 formed from the upper portions of the side walls of the body, two of which are adjacent each end of said body in opposed relation. The lid has notches 6', Fig. 4, to permit said lid to pass over the keepers which then project above the lid a sufficient distance to allow the ends of the latches to pass under the inturned ends of said keepers.

On top of the lid 6 is fixed a bridge 9 having a portion spaced from the outer face of said lid and between said spaced portion of the bridge and opposed lid face is a nut 10 screwed onto the threaded stem 11, attached to a razor blade holder or container 12, which stem projects through aligned holes in the lid and bridge.

The razor blade holder or container 12 includes a plate 13 having a reverse flange 14 along its upper edge to form a track groove and inturned lugs 15 at the bottom adjacent the ends to constitute a segmental track groove. One edge of a safety razor blade 16 is inserted laterally under the flange 14 into the groove and portions of said blade slipped over the lugs and dropped into the segmental track groove. Finally a closure plate 17 is slid endwise into the space between the razor blade and the flange 14 at the top of the holder and the lugs 15 at the bottom of said holder to clamp the razor blade in place with a cutting edge exposed at the bottom of the holder.

The control box or body 5 has channel tracks 18 on the inside at the ends thereof and said tracks are perpendicular to the lid 6. These channel tracks run from the top of the body to locations some distance below the bottom of said body in the form of extensions. The ends of the blade holder slidably fit in said channel tracks and may be moved up and down by the proper manipulation of the nut 10.

Individual strand members 19 are formed from sections of appropriate wire fashioned to substantially triangular shape to constitute a guard and the ends of the base portions thereof are fixed to opposite sides of the control box or body 5 with acute angular portions 20 centered directly below the blade holder 12 so that when a

blade is assembled in said holder and the latter adjusted the cutting edge will be equally spaced from both of the inclined sides of the guard. The strand members 19 are braced by reinforcing wires 19.

A handle 21 is provided at one end of the body 5 whereby the device may be used somewhat after the manner of a hair brush.

In order to assist the user of the hair cutter to adjust the blade for removing the desired amount of hair, the blade holder or container 12 may have suitable index marks 22, such as lines and associated numerals, thereon for cooperation with the lower edge of the control box or body 5. These index marks may be on any desirable portion of the blade holder and, for illustrative purposes only, they are shown as being scribed on the face of the closure plate 17 at one end thereof.

To assemble a razor blade in the hair cutter or replace a dull one with a new blade, the lid or cover 6 is unfastened and then removed from the body or control box. As the lid is bodily lifted the blade holder will be moved upwardly in the channel tracks 18 and finally withdrawn therefrom. With the blade holder separated from the body or control box the closure plate 17 can be withdrawn from its tracks and a razor blade 16 inserted or removed and replaced by another and the closure plate slipped into position. Subsequently the blade holder, with a razor blade therein, is inserted in the channel tracks 18 and propelled forwardly until the lid 6 is seated at which time it is secured in place by the latches 7. After the parts have been properly assembled the cutting edge of the razor blade may be adjusted relatively to the slanting sides of the guard by turning the nut 10 in the proper direction which will move said blade 16 towards or away from the angle 20. When the cutting edge of the blade is close to the angle 20 longer portions of hair will be cut from a person's head than when said cutting edge is further removed from said angle 20.

In actual practice, after the cutting edge of the razor blade has been properly adjusted for cutting the hair to the desired length either slanting side of the guard is placed against the scalp and drawn thereover causing the person's hair to enter the interstices of said guard and the hair ends cut off leaving the remaining hair of the preselected length. After one side of the hair has been cut the hair cutter is shifted to the opposite side of the person's head and the other slanting side of the guard placed against the scalp and the operations repeated without readjusting the cutting edge of the blade. This insures that the hair on both sides of the head will be uniform after cutting.

It is to be particularly noted that the adjustments of the razor blade holder are accomplished from the top of the control box or body thereby eliminating the necessity of having protruding parts on the sides which might interfere with the proper contact of the guard with the scalp. Attention is also called to the fact that the same cutting edge of the razor blade can be utilized during one hair cutting operation without either reversing or inverting the hair cutter for employment on opposite sides of the head.

Of course I do not wish to be limited to the exact details of construction herein shown and described as these may be varied within the scope of the appended claims without departing from the spirit of my invention.

Having described my invention what I claim as new and useful is:

- 5 1. A hair cutter comprising a control box having an opening at the top and open at the bottom, a lid detachably secured to said control box for normally closing the opening at the top thereof, a razor blade holder slidably mounted for vertical movements in the control box and having a portion projecting through the lid, means connected to said projecting portion and coacting with the lid for vertically adjusting the blade holder, a guard comprised of a plurality of individual wire strands each fashioned into substantially triangular shape to provide an acute angle and fixed at the base to opposite sides of the control box with said angle located centrally below the blade holder, and a handle on one end of said control box.
- 10 2. A hair cutter comprising a hollow oblong control box having an opening at the top and open at the bottom, vertical channel tracks on the ends of said control box within the same and extending below the bottom thereof, a razor blade holder adapted to hold a safety razor blade with a cutting edge exposed below the blade holder, said blade holder being slidably mounted in the channel tracks, a threaded stem projecting from the blade holder and extending above the top of the control box, a lid to normally close the opening at the top of said control box, a bridge on the exterior of the lid with a portion spaced therefrom, said lid and the spaced portion of the bridge having aligned holes to receive the stem of the blade holder, a nut on said stem between the face of the lid and the spaced portion of the bridge whereby the blade holder is adjustably attached to said lid, means to detachably secure the lid to the top of the control box to normally close the top opening, a guard consisting of a plurality of individual wire strands each fashioned into substantially triangular shape to provide an acute angle and an opposed base, said strands being fixed at their bases to opposite sides of the control box adjacent the top of said control box and providing converging slanting guard sides running to the acute angle which is located centrally below the blade holder, and a handle projecting from one end of the control box in a straight line therewith.
- 15 3. The structure according to claim 2 wherein the means for detachably securing the lid in place consists of inturned keeper hooks on the sides of the control box at the top thereof and adjacent both ends, the lid having apertures whereby said lid may be passed over the keepers and seated on the top of the control box, and latches pivoted on the exterior face of the lid for cooperation with the keepers.
- 20 4. The structure according to claim 2 wherein the blade holder consists of a back plate, a reversely bent flange along the upper edge of said back plate, a reversely bent lug on the lower edge of said back plate adjacent the ends thereof, said flange and lugs constituting a support for a safety razor blade with a cutting edge exposed below the lower edge of said back plate, and a closure plate slidably endwise into the flange and lugs to clamp the razor blade in place.
